US00D884653S

(12) **United States Design Patent** (10) **Patent No.:** **US D884,653 S**
Kufner et al. (45) **Date of Patent:** **** May 19, 2020**

(54) **ELECTRICAL CONTACT ELEMENT**

(71) Applicant: **STAUBLI ELECTRICAL CONNECTORS AG**, Allschwil (CH)

(72) Inventors: **Tom Kufner**, Riehen (CH); **Philipp Alexander Strehler**, Basel (CH); **Fabian Hilti**, Ziefen (CH); **Lucas Wirz**, Basel (CH)

(73) Assignee: **STAUBLI ELECTRICAL CONNECTORS AG**, Allschwill (CH)

(**) Term: **15 Years**

(21) Appl. No.: **29/641,184**

(22) Filed: **Mar. 20, 2018**

Related U.S. Application Data

(62) Division of application No. 29/585,526, filed on Nov. 25, 2016, now Pat. No. Des. 830,974.

(57) **CLAIM**

The ornamental design for an electrical contact element, as shown and described.

DESCRIPTION

FIG. 1 is a perspective view of a first embodiment of an electrical contact element showing our new design;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof;

FIG. 8 is an alternative view of the first embodiment of an electrical contact element with ends unconnected;

FIG. 9 is a perspective view of a second embodiment of an electrical contact element showing our new design;

FIG. 10 is a top view thereof;

FIG. 11 is a bottom view thereof;

FIG. 12 is a front view thereof;

FIG. 13 is a rear view thereof;

FIG. 14 is a right side view thereof;

FIG. 15 is a left side view thereof; and,

(Continued)

FIG. 16 is an alternative view of the second embodiment of an electrical contact element with ends unconnected.
